INVENTOR
EDWARD J. McGRAW
BY *George B. Wilcox*
ATTORNEY

UNITED STATES PATENT OFFICE.

EDWARD J. McGRAW, OF SAGINAW, MICHIGAN.

RECEPTACLE FOR GOLF-PLAYERS' ACCESSORIES.

Application filed April 18, 1927. Serial No. 184,433.

This invention is an article for use of golf players as a pocket convenience and comprises a receptacle for tees and matches.

An object of the invention is to provide a receptacle that is of light weight, compact and capable of being made either of soft material or of inflexible material, the construction being such that in either case the tees will not accidentally come loose and the matches or other articles will stay in place until needed, notwithstanding the receptacle has no retaining cover for that purpose.

This invention is a continuation in part of the invention described and claimed in my co-pending application, Serial No. 144,055, and includes a novel device for releasably holding the tee in its pocket or hole, preventing its becoming accidentally loosened, or jarred out, yet permitting it to be readily withdrawn without sticking or creating a suction effect that would interfere with its removal.

Furthermore, the tee-retaining device is so constructed that it will be effective whether the receptacle is made of soft flexible rubber or of hard material, such as cast aluminum.

Another object is to provide a pocket for releasably holding a supply of wooden matches so they will lie flat against the face of the receptacle and for holding packets of paper matches so they cannot be pushed into the pocket far enough to cover up their strips of abrasive.

The complete article is light, thin and convenient to carry in the user's pocket, or in the pocket of a golf bag.

With the foregoing and certain other objects in view, which will appear later in the specification, my invention comprises the devices described and claimed and the equivalents thereof.

In the drawings Fig. 1 is a perspective view of my receptacle, showing the manner of inserting and removing the golf tees.

Fig. 2 is a longitudinal section on line 2-2 of Fig. 6.

Fig. 3 is a side view of the receptacle.

Fig. 4 is a longitudinal section on line 4-4 of Fig. 2.

Fig. 5 is a similar section on line 5-5 of Fig. 2.

Fig. 6 is a transverse section on line 6-6 of Fig. 4.

Fig. 7 is a similar section on line 7-7 of Fig. 5.

Fig. 8 is a fragmentary, part sectional plan view of the receptacle with a container for paper matches applied thereto.

Fig. 9 is a similar view with a supply of wooden matches therein.

Fig. 10 is a detail showing a pocket for receiving a tee.

The front wall 1 of the receptacle is provided at its side edges with two retaining ribs 2, 2 and at one end is formed with a pocket 3 for receiving an end of a packet of paper safety matches 4, as shown in Figs. 1 and 8, or a supply of wooden matches, as shown in Figs. 4 and 9, or for holding any other suitable article, such as a score card, a thin compact, a mirror, a score pencil, a few cigarettes etc. The shape and size of the pocket 3 will be determined by the kind of article it is to contain, but for purpose of illustration a preferred form is illustrated as a match container.

The pocket is defined by an outer wall 6, an end wall 7 and two side walls 8, 8. The inner face of the outer wall 6 is formed with a rib 9 parallel to its margin for engaging an ordinary match 5 above its head, as indicated in Fig. 4, to yieldingly hold the match head in place and to keep the other end of the match stick snugly pressed against the face of the front wall 1 of the receptacle.

For that purpose the rib 9 is preferably made of compressible yielding material, such as soft rubber, and if preferred, the entire outer wall 6 of the pocket 3 may be of the same material.

The rib 9 does not necessarily extend clear across the face of the receptacle, but may be made thinner at the edges, as shown at 9^a in Fig. 7, so that when matches are inserted into the pocket near its side walls 8, 8 they will not have the effect of bulging the wall of the pocket outward near its middle. Stop pieces 10, 10 are also provided within the pocket at its side walls 8 to abut against the entering edges of a packet of paper matches, preventing the packet being pushed into the pocket 3 to such a depth as to conceal the abrasive strip 4^a on the packet, as shown in Fig. 8. If ordinary wooden matches are used, an abrasive strip 11 may be inserted in the back face of the receptacle in the usual manner.

The pockets for receiving the tees 12 each consist of a bore or hole 13, preferably slightly larger than the diameter of the cy-

lindrical shank, or the hole 13 may be of slightly different shape from the tee, so as to provide an air space around the tee and avoid any suction-like action that might otherwise interfere with the removal of the tee. Such suction can also be prevented by providing an air hole 13^a clear through the receptacle, as shown by dotted lines in Fig. 10. The outer end of the bore is formed as 10 a countersunk opening 14 to receive the tee head, and the inner end 15 of the bore is substantially rectangular in cross section, as shown in Figs. 4, 5, 10, its width being preferably the same as the diameter of the bore 15, but its thickness being less, so that the tapered end of a tee will be wedged between the two side walls of the rectangular part of the hole 15.

If the receptacle is made of flexible material, such as soft rubber, these side walls 15^a will yield back when the tapered end of the tee is pushed between them.

If the receptacle is made of non-flexible material, such as cast aluminum or bakelite, 25 the tapered end of the wooden tee will be slightly compressed when pushed in and thereby becomes sufficiently wedged to remain in place although the tee is easily removable.

30 When the tees are inserted from opposite sides of the receptacle, as shown in Figs. 1 and 2, they are in staggered relation. A section taken on line 5—5 of Fig. 2 then shows alternate round and rectangular openings, illustrated in Fig. 5, and a similar section on line 4—4 of Fig. 2 shows rectangular openings only, as illustrated in Fig. 4.

When the invention is in use individual tees are inserted in the respective tee openings with their pointed ends engaging the side walls of the rectangular openings and slightly force these walls apart, provided the material of the container is flexible, or by slightly compressing the material of the tee 40 if the material of the container is unyielding. Thus the tee is slightly pinched near its point while its cylindrical shank is loosely received in the bore of the tee opening. The tee projects somewhat outside the wall, 50 so it can be pulled loose with a slight movement and is then free to be drawn out of its hole, or dropped out by tilting the receptacle.

The tees may be arranged in staggered 55 relation, as shown in Figs. 1 and 2, or in any other convenient way.

Having thus described my invention, what

I claim and desire to secure by Letters Patent is:

1. A container of the class described comprising a body formed with holes to receive tees, a face of said body provided at one end with a pocket having an outer wall of flexible material, the inner face of said wall provided with a marginal rib thinner at the side edges of said pocket, stop pieces within the pocket adjacent its side walls, the edge walls of said container formed with tee-receiving holes, each hole providing an air space along a tee received therein, the inner end of each hole of substantially rectangular cross section adapted to releasably hold the tapered end of said tee when wedged therein, for the purposes set forth. 75

2. A container of the class described comprising a body formed with holes to receive tees, a face of said body provided at one end with a pocket having an outer wall, the inner face of said wall provided with a marginal rib or flexible material, stop pieces 80 within the pocket adjacent its side walls, the edge walls of said container formed with tee-receiving holes, each hole providing an air space along a tee received therein, the inner end of each hole of substantially rectangular cross section adapted to releasably hold the tapered end of said tee when wedged therein, for the purposes set forth.

3. A container of the class described comprising a body formed with holes to receive tees, a face of said body provided at one end with a pocket having an outer wall, the inner face of said wall provided with a marginal rib of flexible material thinner at the side edges of said pocket, stop pieces with 90 in the pocket adjacent its side walls, the edge walls of said container formed with tee-receiving holes, the inner end of each hole of substantially rectangular cross section 95 adapted to releasably hold the tapered end 100 of said tee when wedged therein, for the purposes set forth.

4. A container of the class described comprising a body formed with holes to receive tees, a face of said body provided at one end 105 with a pocket, stop pieces within the pocket adjacent its side walls, the edge walls of said container formed with tee-receiving holes, the inner end of each hole of a cross section adapted to releasably hold the tapered end of said tee when wedged therein, 110 for the purposes set forth.

In testimony whereof, I affix my signature.
EDWARD J. McGRAW.
